US00D457163S

(12) United States Design Patent **(10) Patent No.:** **US D457,163 S**
Peiker **(45) Date of Patent:** **** May 14, 2002**

(54) CRADLE FOR PERSONAL DIGITAL ASSISTANT

D411,824 S * 7/1999 Wilson, Sr. et al. D13/108
D412,494 S * 8/1999 Tamaki et al. D14/314
D450,707 S * 11/2001 Francavilla et al. D14/434

(76) Inventor: **Andreas Peiker**, Max-Planck-Strasse 32, D-61381 Friedrichsdorf (DE)

* cited by examiner

(**) Term: **14 Years**

Primary Examiner—Kay H. Chin

(74) Attorney, Agent, or Firm: Venable; Gabor J. Kelemen; Robert Kinberg

(21) Appl. No.: **29/142,946**
(22) Filed: **Jun. 6, 2001**

(57) CLAIM

(30) Foreign Application Priority Data

The ornamental design for a cradle for personal digital assistant, as shown and described.

Dec. 7, 2000 (DE) 400 11 401

(51) LOC (7) Cl. **14-02**

DESCRIPTION

(52) U.S. Cl. **D14/434; D14/341**

FIG. 1 is a perspective view, from the front, of my new design.

(58) Field of Search D14/432-434,

FIG. 2 is a perspective view, from the rear, of my new design.

D14/439-447, 300, 356, 357, 341-355;
D13/184, 199; 361/679-687; 200/5 R, 5 A,
6 R, 6 A

FIG. 3 is a front elevational view thereof.

(56) References Cited

FIG. 4 is a left side elevational view thereof.

U.S. PATENT DOCUMENTS

FIG. 5 is a right side elevational view thereof.

D366,659 S * 1/1996 Ross et al. D14/434
D373,121 S * 8/1996 Deluliis et al. D14/457

FIG. 6 is a top plan view thereof.

FIG. 7 is a bottom plan view thereof; and,

FIG. 8 is a rear elevational view thereof.
